(57) **CLAIM**

The ornamental design for a case enclosure, as shown and described.

DESCRIPTION

FIG. 1 is a top front right isometric view of a case enclosure showing our new design;

FIG. 2 is a bottom rear right isometric view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines in the drawings represent environmental subject matter and form no part of the claimed design.
